US00D786974S

(12) **United States Design Patent** (10) **Patent No.:** **US D786,974 S**
Lueken (45) **Date of Patent:** **** May 16, 2017**

(54) **PAIR OF ADVERTISING PANELS WITH
ROUNDED MARKER FOR SHOPPING CART
CORRAL**

(71) Applicant: **Starlite Media, LLC**, New York, NY (US)

(72) Inventor: **Harold Lueken**, New York, NY (US)

(73) Assignee: **Starlite Media, LLC**, New York, NY (US)

(**) Term: **14 Years**

(21) Appl. No.: **29/518,903**

(22) Filed: **Feb. 27, 2015**

(51) **LOC (10) Cl. 20-03**

(52) **U.S. Cl.**

USPC **D20/19; D20/42**

(58) **Field of Classification Search**

(57) **CLAIM**

The ornamental design for a pair of advertising panels with rounded marker for shopping cart corral, as shown and described.

DESCRIPTION

FIG. 1 is a perspective view of the pair of advertising panels with rounded marker for shopping cart corral;

FIG. 2 is a left side view thereof;

FIG. 3 is a right side view thereof;

FIG. 4 is a front view thereof;

FIG. 5 is a rear view thereof;

FIG. 6 is a top view thereof;

FIG. 7 is a perspective view of the pair of advertising panels with rounded marker for shopping cart corral;

FIG. 8 is a left side view thereof;

FIG. 9 is a right side view thereof;

FIG. 10 is a front view thereof;

FIG. 11 is a rear view thereof; and,

FIG. 12 is a top view thereof.

The broken line showings of the shopping cart corral in the figures are for the purpose of illustrating an environment only and form no part of the claimed design.

1 Claim, 10 Drawing Sheets
